UNITED STATES PATENT OFFICE.

WILLIAM OWEN, OF PITTSBURGH, PENNSYLVANIA, ASSIGNEE TO PITTSBURGH PLATE
GLASS COMPANY, A CORPORATION OF PENNSYLVANIA.

MACHINE FOR ROUNDING THE EDGES OF SHEETS OF MATERIAL.

Application filed April 8, 1926. Serial No. 100,606.

The invention relates to machines for rounding or beveling the edges of sheets, such as the glass sheets used in automobile wind shields and bodies. The principal objects of the invention are the provision of a machine of simple construction; (1) which will operate at large capacity for a long period of time without any requirement for replacing or resurfacing the abrading wheels; (2) in which the roughing wheels, which bear the brunt of the work are self-dressing, and may be used until worn out without redressing; (3) in which chipping of the edges of the sheets is avoided and uniformly rounded edges with well finished surfaces are secured; and (4) in which improved means are provided for carrying the sheets over the surfacing wheels and for maintaining the glass sheets in proper relation to the grinding wheels. Certain embodiments of the invention are shown in the accompanying drawings, wherein:

Figure 1 is a side elevation of the complete machine. Fig. 2 is a plan view. Fig. 3 is a section on the line III—III of Fig. 1. Fig. 4 is a section on the line IV—IV of Fig. 2. Fig. 5 is an enlarged detail section through one of the cup grinding members. Fig. 6 is a detail plan view. Fig. 7 is a detail sectional view on the line VII—VII of Fig. 6. Fig. 8 is a detail plan view of the construction shown in Figs. 6 and 7. Fig. 9 is a diagrammatic view showing the relative positions of the cup grinding wheels and their relation to the glass sheet whose edge is being rounded. Fig. 10 is a section on the line X—X of Fig. 1. Fig. 11 is a section on the line XI—XI of Fig. 1. Fig. 12 is an enlarged detail section taken in the same plane as Fig. 11. Fig. 13 is an enlarged plan view at the left hand end of the machine of Fig. 1. Fig. 14 is an enlarged section on the line XIV—XIV of Fig. 13. Figs. 15 and 16 are detail views showing a modification, Fig. 15 being a plan view and Fig. 16 being a transverse section. And Fig. 17 is a transverse section through a modified form of construction.

50 The machine as illustrated and described comprises a roughing unit having six surfacing wheels and a finishing unit having four surfacing wheels, but the number of wheels may be varied to meet requirements.

Referring to Figs. 1 and 2, the roughing unit comprises the pairs of wheels 1, 1, 2, 2, and 3, 3, while the finishing unit comprises the four wheels 4, 5, 6 and 7. In operation, the glass sheets 8, 8, 8, etc., whose edges are to be rounded to the contour indicated at A in Fig. 9, are carried longitudinally over the ten wheels from the left hand end of the machine to the right hand end by means of two endless belts 9 and 10, such belts being provided with clamping means for gripping the opposite sides of the plates and supporting them during their passage along the machine. The pairs of roughing wheels 1, 1, 2, 2, and 3, 3 practically shape the edge of the sheet as they are placed at different angles and, therefore, grind a plurality of bevels which merge into each other, as indicated in Fig. 9. The edge is, of course, still unfinished after passing these wheels, but the major portion of the work is accomplished, and what remains is finished by the first two finishing wheels 4 and 5, which are circumferentially grooved to the exact contour which it is desired to give the edges of the glass sheets. The final wheels 6 and 7 are preferably polishing wheels, ordinarily made of a rubber composition and supplied with a polishing mixture, such as water and pumice. This gives the edges their final finish, after which they are carried along by the chains 9 and 10 to the end of the machine and there released. During the passage of the plates from one end of the machine to the other, they are unsupported, except for the clamping means which grip their opposite sides, and the chains 9 and 10 which carry the gripping means are so guided and supported that the lower edges of the plates which are being surfaced move ahead throughout their travel on substantially a right line, the only deviation from such line being that incident to the grinding away of the material. The ten abrading and finishing wheels are all made vertically adjustable independently, so that each wheel can be so positioned as to do its proper share of work, thus distributing the wear in as uniform a manner as is possible between the various wheels. The glass plates are very firmly gripped by the clamping devices carried by the chains 9 and 10, so that there is substantially no slipping of the plates to cause them to deviate from

their proper lines of movement. This security in the support of the plates is facilitated by the use of gripping devices, as later described, which are slightly yielding, so that under the force applied to the plates by the grinding wheels, there is not the same tendency for the plates to slip and change their positions, as would be the case if they were supported with absolute rigidity upon the chains. Under these conditions of use, any interruptions of the operation of the machine for replacement and repair are slight. The roughing wheels 1, 1, 2, 2, and 3, 3, are self-dressing, as later set forth, and may be used until worn out without redressing, while the wheels 4 and 5, which do require redressing, need this operation only at long intervals because the roughing wheels preceding these wheels reduce the edges of the sheets to such an extent that the work left for the finishing wheels is relatively slight, and the wear upon the wheels correspondingly slight and very uniform.

25 The carrier chains 9 and 10 which support the glass sheets and carry them over the surfacing wheels extend around the pairs of sprocket wheels 11 and 12 and 13 and 14 (Fig. 2) carried by the vertical shafts 14^a, 15, 16 and 17. The shaft 14 is driven from the motor 17^a through the intermediary of the chain belt 18 and worm wheel and worm reducing gearing in the casing 19, while the shaft 15 is driven from the shaft 14^a by 30 means of a spur gear 21 on the shaft 14^a meshing with a similar gear 21 on the shaft 15. The chain comprising the endless carriers is made up of side plates 21 and 22, as indicated in Figs. 12 and 13, connected 35 by pintles 23 carrying rollers 24. The inner flights of the two chains are supported in guide members 25 and 26 secured to the base plate 27 of the machine, as indicated in Figs. 11 and 12, and carry the U-shaped 40 members 28 upon which are mounted the clamping devices for the glass sheets 8, 8, 8, etc. These clamping devices consist of cups 29 of rubber composition carried by the bolts 30 extending slidably through the U-shaped 45 members 28 and held yielding in forward position by means of the relatively stiff coil springs 31. The upper portions of the sheet are steadied against lateral movement by means of the plates 32, 32 (Fig. 11) 50 mounted upon the channels 33, 33 and provided at their inner edges with the rubber pads 34, 34.

The glass plates 8, 8, 8, etc. are positioned 55 between the clamping devices on the carrier chains 9 and 10 by placing them in the runway 35 shown in detail in Figs. 13 and 14. This runway comprises a channel 36 in which are mounted a pair of wood strips 37, 37 spaced apart and provided at intervals 60 with rubber rolls 38 pivoted upon the pintles 39. The operator places the plate which is to be gripped between the chains upon the rollers 38 and moves it along horizontally until it is gripped by the rubber cup members 29. The bottom of the runway, which thus guides the plates to the gripping chains, is accurately positioned with respect to the cutting surfaces of the abrading wheels, so that when the sheet is carried over the abrading wheels, just the proper amount of cutting 75 action is applied by the wheels. As heretofore stated, each wheel is adjusted at a vertical position, such that it will do its proper proportion of cutting, provided the glass sheet is securely held against vertical movement and guided in a right line in its passage through the machine. The gripping devices, including the rubber cup members 80 29 and the chains are designed to support the sheet in the manner indicated. The cups grip the glass very firmly, so that under the action of the abrading wheels, there is no slipping, and the glass is pressed yieldingly against the wheel with just the proper 85 amount of pressure to give the desired speed 90 of cutting without forcing the work and causing chipping. At the same time, the support afforded by the cups is slightly yielding, which reduces the danger of the plates being caused to slip between the cups 95 and reduces the danger of chipping which would occur if the plates were rigidly held. The guideway 35 makes it easy for the operator to feed the plates with very slight effort 100 and with the assurance that each plate will be properly positioned between the carrier chains, and when the sheets have passed through the machine, they are automatically freed from the gripping devices so that the 105 labor of removing them from the machine 110 is reduced to a minimum.

In order to steady the lower portions of the plates 8, 8, 8, etc. as they pass over the sets of roughening wheels 1, 1, 2, 2, and 3, 3, a pair of longitudinally extending guides 115 40, 40 (Figs. 2 and 11) are employed, such guides being in the form of a pair of rods covered with rubber tubing and located closely adjacent the lower edges of the glass sheets. Rolls are preferably employed for 115 this purpose instead of non-rotating guides, as they give a longer life, the rolls being rotated as the work progresses and presenting new surfaces for wear. The rolls grip the sides of the plate lightly and support it 120 during the grinding operation, thus reducing the tendency to chip and break and maintaining the edge of the sheet against lateral deflection under the pressure of the grinding wheels. In order to accommodate 125 different sizes of glass, these rolls are preferably mounted, so that they may be adjusted toward and from each other and are provided with yielding holding means so that 130 they will adjust themselves automatically to 130

glass of varying thickness. The method of mounting is shown in Figs. 6 and 7. As here shown, the ends of the rolls 40, 40 are pivoted in blocks 41, 41 carried upon vertical pins 42, 42, and such pins are mounted at their lower ends in a disc 43. By rotating the discs at the two ends of the rolls, the rollers may be adjusted toward and from each other, and this rotation is accomplished by means of a lever arm 44 pinned to the downwardly extending shank 45 of the disc 43. This lever arm is adjusted by means of the threaded rod 46 pivoted to the arm 44 and carrying the nuts 47. A spring 48 intermediate the bracket 49 and the nuts 47 serves to hold the lever arm 44 and the rolls 40, 40 in yielding contact with the glass sheets passing therebetween. An adjustable stop bolt 50 serves to limit the movement of the rolls toward each other, so that the rolls are always separated for the reception of the oncoming glass sheets.

The rolls 40 below the gripping means on the chains 8 and 9 in conjunction with the steady plates 32, 32 (Fig. 11) serve to hold the glass plates very securely against vibration and against lateral movement, while the gripping devices, as heretofore pointed out, securely maintain the plate against vertical movement, thus giving the glass plates proper support in all directions during the grinding operation. This support of the plate is particularly desirable in connection with the roughing wheels 1, 1, 2, 2, and 3, 3 which impose more strain upon the plates than is the case with the grooved wheels 4, 5, 6 and 7, which latter by their form more or less guide the edge of the glass plates and give them support against lateral vibration.

The arrangement of the roughing wheels will be understood by reference to Fig. 9 in connection with Figs. 1, 2, 5 and 11. The wheels 1, 1 lie at the same angle to the horizontal, but on opposite sides of the glass sheet. Similarly as to the wheels 2, 2, and 3, 3, whose angles depart from those of the wheels 1, 1. The relative angles of the wheels will be seen by reference to Fig. 9 which shows the three wheels which act upon one corner of the plate, the other three wheels being similarly disposed on the other side of the center line B—B. Cup wheels are preferably used, as such wheels are self-dressing and may be used until worn out without any requirement for resurfacing or truing up. These wheels may be of any suitable abrading material of a fineness such that the abrading action does not cause a chipping of the glass. As will be seen by reference to Fig. 5, the axis of rotation C of each wheel is slightly tilted from the vertical so that the grinding surface of the wheel lies at a slight angle to the edge of the glass which is indicated by the dotted line D of Fig. 5. As a result, only the por-

tion of the wheel to the left of the axis of rotation C (Fig. 5) engages the glass, the other half of the wheel lying to the right of the axis of rotation being out of contact with the glass. I have found that the cutting action is better when the wheels are tilted in this manner and any chipping incident to the operation is reduced. The wheels are also preferably rotated so that the abrading surface cuts downward with respect to the glass, which method of operation also tends to reduce any chipping as compared with an operation in which the direction of rotation is reversed. Each wheel is mounted upon an axle 51 (Fig. 5) carried in a sleeve 52 and rotatable upon the roller bearings 53, 53. The sleeve is mounted for vertical adjustment in a member 54 bolted to the casting 55 and the casting is supported upon a suitable underframing 56. The member 54 is split so that when tightly clamped by the bolts 57, the sleeve 52 is held securely against vertical movement. The sleeve 52 is provided at its upper end with a guard casing 58 and the lower side of this casing is engaged by a stop screw 59 which serves as a means for adjusting the vertical position of the grinding wheel and positively holding it against downward movement. The sleeve 52 is held against rotation by means of the hollow screw 60 which is provided with a passage for supplying grease to the cavity 61 surrounding the axle 51. The grinding wheel is clamped to the axle by means of the nut 62 and suitable protectors 63, 63 are provided at the ends of the axle to guard the bearings against the admission of moisture or grit. The axles of the grinding wheels are preferably driven by means of the flexible shafts 64, 64, 64, etc., terminating at the stub shafts 65, 65, 65, etc., carried by the gear casing 66. These stub shafts are provided with intermeshing spur gears 67, 67, 67, etc., one of which has its end extended and is provided with a sprocket around which passes the silent chain 68 driven from the motor 69.

After the glass sheets have passed the roughing unit, they are carried over the four finishing wheels 4, 5, 6 and 7, all similar in construction, except that the last two wheels 6 and 7 are made of rubber composition instead of an abrasive. The wheels are all mounted for independent vertical adjustment upon a supporting base comprising the longitudinal channels 70 and plate 71 (Figs. 1 and 10). The wheels are carried upon the ends of the shafts 72, 73, 74 and 75 and such shafts are journaled in vertically adjustable frames, such as the framing 76, shown in cross section in Fig. 10. A description of the mounting as shown in Fig. 10 will serve for all of the mountings. The frame 76 is supported upon the vertical shafts 77, 77

5 pinned against rotation at their upper ends and extending down through the worm wheels 78, 78 swiveled upon the plate 71. These worm wheels are adapted to be rotated by means of a pair of worms carried by a transverse shaft 79, which is provided with a squared end 80 for the application of a turning lever. In this manner, the wheel may be adjusted vertically so that it 10 engages the lower edge of the glass sheets with just the proper amount of pressure. The shaft 75 is driven from the motor 81 by means of a belt 82 (Fig. 2), and the shafts 72, 73 and 74 are driven from the shaft 75 15 through the intermediary of the belts 83, 84 and 85, as shown in Fig. 2, the shafts being provided with suitable pulleys over which the belts pass. The wheels 4, 5, 6 and 7 are each provided with a casing 86 having a 20 removable cover plate 87 and supplied with water through a connection 88. Provision is made for cleaning the casing through the opening 89 closed by the gate 90 which is hinged at 91 and held in closed position by 25 the bolt 92. Each of the wheels 4, 5, 6 and 7 is circumferentially grooved, as indicated at 93, the contour of this groove corresponding to that which it is desired to give to the edges of the glass plates. In order to secure 30 a polishing action by the wheels 6 and 7, the casings surrounding such wheels are supplied with a mixture of water and pumice. The frame members 76 which carry the shafts 72, 73, 74 and 75 are guided and supported in their various positions of vertical 35 adjustments by means of the triangular members 94, 94, spaced apart to form guide-ways for the frame members and bolted at their lower ends to the base of the machine.

40 In order to steady the lower edges of the plates as they pass over the grooved abrading wheels, guide members 95, 95 are preferably employed (Fig. 17), such guide members being Z-shaped in cross section and secured to the frame members 96, by means of 45 the bolts 97. These members are preferably of rubber composition and either touch the sides of the glass sheet or come closely adjacent thereto. The construction shown in 50 Fig. 17 involves a modification of the gripping devices heretofore described in connection with Figs. 11 and 12 in that the cup shaped members 98, 98 are secured directly to brackets 99, 99 carried by the chain links 55 100. The springs 31 of the Fig. 12 construction are thus dispensed with, and the cup members entirely relied upon to give the necessary yielding grip and to take care of plates of varying thickness. The yielding function 60 in these cups may be augmented by making them larger in diameter and with somewhat thinner side walls. In other particulars, the construction shown in Fig. 17 is the same as that heretofore described except that a 65 slightly different means for guiding the up-

per portion of the sheet is employed. The means here employed consists of a plurality of spaced brackets 101, each of which carries a pair of wood strips 102, 102, in which are mounted vertical pins 103. These pins carry 70 rubber rollers 104 which engage the sides of the glass sheet. As the glass plates emerge from the carrier chains 9 and 10, they are received upon a runway 35* (Fig. 1) similar to the runway 35 heretofore described and illustrated in Figs. 13 and 14, where they are grasped by an operator 75 and removed from the machine.

Figs. 15 and 16 illustrate a modified carrier construction for glass plates, such carrier arrangement involving the use of only one chain flight instead of the two flights of the construction heretofore described. As indicated in Fig. 16, the chain 105 is guided in a horizontal frame member 106, the top 80 plates 107 of the links being provided with U-shaped members 108 in which are slidably mounted the bolts 109. These bolts have transverse heads 110 and such heads are covered with rubber tubing 111. The parts 112 of the bolt is also provided with a piece of rubber tubing 113. The bolt is pressed yieldingly to the right (Fig. 16) by means of a spring 114 lying between the member 108 and the head of the bolt. In the use of the 85 device, the gripping devices are arranged as indicated in Fig. 15, a part of the bolts having their transverse heads 110 arranged vertically, as indicated at X—X—X, while two other of the bolts have their heads arranged 90 horizontally, as indicated at Y—Y, the springs 114, 114 in these latter members being under compression, since the bolts have been pushed to the left, so that the glass sheet is firmly gripped at its edges between 95 the bolts having their heads horizontal and those having their heads vertical, as indicated in Fig. 15. This method of gripping the plates requires a much larger amount of labor on the part of the operator than the 100 arrangement of Figs. 11, 12 and 13 heretofore described due to the fact that the holding bolts must be adjusted and clamped to each plate. The glass plates may, however, be securely supported and carried in a right 105 line by this general arrangement and illustrates the possibility of accomplishing the desired result by the use of a single carrier chain 1 instead of the two chains 9 and 10 of the first form of construction. 110

120 While the machine is designed primarily for rounding the edges of glass sheets, as heretofore described, it may also be used to good advantage for beveling the edges of sheets, the same cutting wheels being used, 125 but only the set on one side of the sheet being required and the members of such set all being inclined at the same angle and arranged so that they cut successively. A part of these wheels may be composed of polish- 130

ing material, and in this beveling operation, the series of circumferentially grooved grinding wheels are of course not required.

What I claim is:

5. 1. A machine for rounding the edges of glass sheets comprising, means for supporting a glass sheet and carrying it ahead, and a roughing unit in the line of travel of one of the edges of the sheet comprising a series of pairs of driven abrading wheels of cup form having the axes of rotation of each pair oppositely inclined with the planes of rotation of the wheels extending obliquely of the plane of the glass sheet, so that the cutting faces thereof will engage the corner edges of such sheet, the axes of rotation of said pairs of wheels being inclined at different angles, so as to cut bevels from said corners lying at different angles.
10. 2. A machine for rounding the edges of glass sheets comprising, means for supporting a glass sheet and carrying it ahead, a roughing unit in the line of travel of one of the edges of the sheet comprising a pair of driven abrading wheels having their axes of rotation inclined toward each other with the cutting faces of the two wheels extending obliquely of the plane of the glass sheet, and adapted to engage the corner edges of such sheet, and a driven abrading wheel having a circumferential groove in the line of movement of the glass sheet and positioned to engage the edge thereof after it passes the roughing unit.
15. 3. A machine for rounding the edges of glass sheets comprising, means for supporting a glass sheet and carrying it ahead, a roughing unit in the line of travel of one of the edges of the sheet comprising a pair of driven abrading wheels having their axes of rotation inclined toward each other with the cutting faces of the two wheels extending obliquely of the plane of the glass sheet, and adapted to engage the corner edges of such sheet, and a series of driven abrading wheels each having a circumferential groove in the line of movement of the glass sheet and adapted to engage the edge thereof one after another after it passes the roughing unit.
20. 4. A machine for rounding the edges of glass sheets comprising, means for supporting a glass sheet and carrying it ahead, a roughing unit in the line of travel of one of the edges of the sheet comprising a series of pairs of driven abrading wheels of cup form having the axes of rotation of each pair inclined toward each other with the planes of rotation of the wheels extending obliquely of the plane of the glass sheet so that the cutting faces thereof will engage the corner edges of the sheet, said pairs of wheels of cup form being inclined at different angles so as to cut bevels from the corners of the glass sheet lying at differ-
- ent angles, and a second unit comprising a series of driven surfacing wheels, each having a circumferential groove in the line of movement of the glass sheet and adapted to engage the edge thereof one after the other after it passes the roughing unit.
25. 5. In a machine for cutting the edges of glass sheets, a series of driven abrading wheels having their cutting surfaces arranged in alignment and adapted to cut the edges of the sheets carried thereover, and means for moving the sheets over the cutting surfaces of the wheels in vertical position with an edge in contact therewith, comprising a pair of endless driven carriers arranged with a flight of one carrier in opposition to that of the other and with such flights extending along the series of abrading wheels, guide means for said flights for holding them against deflection, and yielding clamping means upon each carrier and adapted to grip the sides of the glass sheets fed therebetween and hold such plates securely against edgewise movement as the sheets are moved over the abrading wheels.
30. 6. In a machine for cutting the edges of glass sheets a series of driven abrading wheels having their cutting surfaces arranged in alignment and adapted to cut the edges of the sheets carried thereover, and means for moving the sheets over the cutting surfaces of the wheels in vertical position with an edge in contact therewith, comprising a pair of endless driven carriers arranged with a flight of one carrier in opposition to that of the other and with such flights extending along the series of abrading wheels, guide means for said flights for holding them against deflection, a runway leading between said flights for guiding the glass sheets into position therebetween, and clamping upon each carrier for engaging the glass, said clamping means being arranged to grip the glass sheets therebetween and hold them yieldingly into engagement with the abrading wheels as they are moved past such wheels.
35. 7. In a machine for cutting the edges of glass sheets, a series of driven abrading wheels having their cutting surfaces arranged in alignment and adapted to cut the edges of the sheets carried thereover, and means for moving the sheets over the cutting surfaces of the wheels in vertical position with an edge in contact therewith, comprising a pair of endless driven carriers arranged with a flight of one carrier in opposition to that of the other and with such flights extending along the series of abrading wheels, guide means for said flights for holding them against deflection, a runway leading between said flights for positioning the glass sheets at the proper level therebetween, and yielding clamping means upon each carrier for engaging the glass, said

- clamping means being arranged to grip the glass sheets firmly against vertical slippage therebetween and to bring them into lateral yielding engagement with the abrading wheels as they are moved past such wheels. 5
8. In a machine for cutting the edges of glass sheets, a series of driven abrading wheels having their cutting surfaces arranged in alignment and adapted to cut the edges of 10 the sheets carried thereover, means for moving the sheets over the cutting surfaces of the wheels in vertical position with an edge in contact therewith comprising driven endless carrier means along the series of wheels, 15 and yielding clamping means arranged to grip the sides of the sheets back from the edges to be cut and to hold such edges in contact with the abrading wheels, and steady means for holding the sheets against lateral 20 movement located intermediate said clamping means and the wheels. 16
9. In a machine for cutting the edges of glass sheets, a series of driven abrading wheels adapted to cut the edges of the sheets 25 carried thereover, means for moving the sheets over the cutting surfaces of the wheels in vertical position with an edge in contact therewith comprising driven endless carrier means along the series of wheels, and yielding clamping means arranged to grip the sides of the sheets back from the edges to be cut and to hold such edges in contact with the abrading wheels, and steady means 30 for holding the sheets against lateral movement located intermediate said clamping means and the wheels, said means comprising two rolls extending longitudinally of the line of movement of the sheets on opposite sides thereof and having yielding surfaces. 35
10. In a machine for cutting the edges of glass sheets, a series of driven abrading wheels adapted to cut the edges of the sheets carried thereover, means for moving the 40 sheets over the cutting surfaces of the wheels in vertical position with an edge in contact therewith comprising driven endless carrier means along the series of wheels, and yielding clamping means arranged to grip the 45 sheets of varying thickness. 46
11. In a machine for cutting the edges of glass sheets, a series of driven abrading wheels adapted to cut the edges of the sheets carried thereover, means for moving the sheets over the cutting surfaces of the wheels in vertical position with an edge in contact therewith comprising driven endless carrier means along the series of wheels, and yielding clamping means arranged to grip the sides of the sheets back from the edges to be cut and to hold such edges in contact with the abrading wheels, and steady means 50 for holding the sheets against lateral movement located intermediate said clamping means and the wheels, said means comprising two rolls extending longitudinally of the line of movement of the sheets on opposite sides thereof and having yielding surfaces. 55
12. In a machine for rounding the edges of glass sheets comprising, means for supporting a glass sheet and carrying it ahead, a roughing unit in the line of travel of one of the edges of the sheet comprising a pair of driven abrading wheels having their axes of rotation on opposite sides of the line of travel of the sheet and arranged so that the rotating surface of one wheel engages one corner of the edges of the sheet and the other wheel engages the other corner of said edge, and a driven abrading wheel having a circumferential groove in the line of movement of the glass sheet and positioned to engage the edge thereof after it passes the roughing unit. 60
- In testimony whereof, I have hereunto subscribed my name this 3rd day of April, 1926. 65

WILLIAM OWEN. 70
